CLAIM

We claim the ornamental design for electron microscope, as shown and described.

DESCRIPTION

FIG. 1 is a front, top and right side perspective view of electron microscope showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front, top, and right side perspective view thereof with the covers opened, the undisclosed portions are not part of the claimed design.
